US0D1078038S

(12) **United States Design Patent** (10) **Patent No.:** **US D1,078,038 S**
(45) **Date of Patent:** **** Jun. 3, 2025**

(54) **BLOOD COLLECTION FUNNEL**

(71) Applicant: **Blackfly Investments, LLC**,
Vancouver, WA (US)

(72) Inventors: **Andrew Chastain**, Vancouver, WA
(US); **Mariko Nakano**, Vancouver, WA
(US); **Charles Sailey**, Vancouver, WA
(US); **Adam Blackwell**, Vancouver, WA
(US); **Peter Flynn**, Vancouver, WA
(US)

(73) Assignee: **Blackfly Investments, LLC**,
Vancouver, WA (US)

(**) Term: **15 Years**

(21) Appl. No.: **29/895,777**

(22) Filed: **Jun. 26, 2023**

(51) LOC (15) Cl. **24-04**

(52) U.S. Cl.

USPC **D24/121**

(57) **CLAIM**

The ornamental design for a blood collection funnel, as
shown and described.

DESCRIPTION

FIG. 1 is a first isometric view of a blood collection funnel;
FIG. 2 is a second isometric view of the blood collection
funnel;

FIG. 3 is a right-side view of the blood collection funnel;

FIG. 4 is a left-side view of blood collection funnel;

FIG. 5 is a front view of blood collection funnel;

FIG. 6 is a back view of the blood collection funnel.

FIG. 7 is a top view of the blood collection funnel; and,

FIG. 8 is a bottom view of the blood collection funnel.

The subject ornamental design, as shown in FIGS. 1-8, is for
a blood collection funnel.

1 Claim, 8 Drawing Sheets
